EAVES FLASHING FOR GUTTER-PROTECTING DEVICES

Filed Jan. 10, 1949

UNITED STATES PATENT OFFICE

2,613,621

EAVES FLASHING FOR GUTTER-
PROTECTING DEVICES

Charles H. Schraeder, Detroit, Mich.

Application January 10, 1949, Serial No. 70,117

6 Claims. (Cl. 108—30)

1

This invention relates to building structures, and in particular to gutter screens and their mountings.

One object of this invention is to provide a gutter-protecting device having a screen and an eaves flashing for holding the screen which will not only prevent leaves or other foreign matter from falling into the gutter or eaves trough but will also prevent water from running back of the gutter at the eaves and thereby prevent streaking of the backboard or facia.

Another object is to provide a gutter protecting device having a screen and eaves flashing of the foregoing character wherein a screen is removably mounted in the flashing so that the gutter may be quickly and easily cleaned.

Another object is to provide a gutter protecting device having a screen and eaves flashing of the foregoing character wherein the flashing is attached to the eaves beneath the lowermost row of shingles or lowermost portion of roofing without the need for special tools.

In the drawings,

Figure 1 is a fragmentary perspective view of the lower edge of a roof and eaves trough or gutter, showing the improved eaves flashing and gutter screen of the present invention; and

Figure 2 is a perspective view of a portion of the eaves flashing used with the gutter screen of Figure 1.

Referring to the drawings in detail, Figures 1 and 2 show the gutter-protecting device, generally designated 10, consisting generally of an eaves flashing 11 and gutter screen 12 for protecting an eaves trough or gutter 13 from the influx of foreign matter, such as leaves, twigs or the like. The device 10 is attached to a roof 14 having rafters 15 to which the roof boards or eaves 16 are nailed in the usual way, and to which the facia board or backboard 17 is attached. Secured to the lower portion of the facia board 17 are the horizontal and vertical eaves boards 18 and 19 respectively. Secured to the roof boards 16 is a layer of roofing paper 20 over which shingles 21 are laid in the usual way. Secured to the facia board 17 is the rear wall 22 of a gutter or eaves trough 23 having a bottom wall 24 and front wall 25, the latter being formed with an inwardly-extending flange 26 having a longitudinal edge 27. The foregoing construction, except for the gutter-projecting device 10, is conventional construction.

The eaves flashing 11 of the gutter-protecting device 10 is formed of sheet metal, such as copper, galvanized iron or the like (Figure 2) and has a top portion or supporting portion 30 of plate-like form adapted to be inserted beneath the lowermost row of shingles 21 and a lower edge of the roofing paper 20 (Figure 1). Extending downward from the top portion 30 is a

5 connecting portion 31 approximately at right angles to the portion 30 and of approximately the thickness of the roof boards 16 and adapted to engage the lower edge 32 thereof. Bent inwardly from the connecting portion 31 is the upper part 33 of a screen-holding portion 34 of U-shaped cross-section, the lower portion 35 of which extends forward and is bent downward as at 36 to facilitate the insertion of the screen 12. The eaves flashing 11 is preferably made in elongated sections of suitable length convenient for manufacture and handling.

15 The gutter screen 12 is also made in elongated sections from wire cloth or the like and has its rearward edge portion 40 inserted in the groove 37 formed between the upper and lower portions 33 and 35 of the screen-holding portion 34. The forward edge portion 41 of the screen 12 is bent back upon itself as at 42 so as to provide a portion resting on the flange 26 of the eaves trough or gutter 13. The extreme forward edge portion 43 of the screen 12 is bent downward from the portion 42 so as to form an abutment adapted to engage the edge 27 of the flange 26 to prevent the rearward portion 40 of the screen 12 from slipping out of the groove 27 in the screen-holding portion 34.

20 In the installation of the invention, the base portion or supporting portion 30 of the flashing 11 is placed against the top surface of the roof boards 16 near the lowermost edge 32, and is pushed upward beneath the roofing paper layer 20 and lower row of shingles 21 until its connecting portion 31 comes to rest against the edge 32 of the lowermost board 16. This causes the screen-holding portion 34 to lie beneath the lower edge portion of the lowermost board 16 with its groove 37 facing downward toward the edge 27 of the gutter flange 26. The flashing 11 is then nailed or otherwise secured in position against the board 16. The workman then grasps a length of the screen 12 and, while lifting the bent portions 43 and 42 above the flange 26, he pushes the rearward edge portion 40 of the screen 12 into the groove 37, springing the screen 12 slightly in order to do this. When he releases the forward edge of the screen 12, the abutment portion 43 drops downward behind the edge 27 of the flange 26 and the reversely bent portion 42 comes to rest upon the flange 26, as shown in Figure 1. The eaves trough or gutter 13 is now protected from being clogged by leaves, twigs or the like, and other objects such as baseballs, or children's toys are prevented from being lost in the eaves trough. The screen 12 also prevents birds from building their nests in the eaves trough 13. Furthermore, the screen-holding portion 34, by reason of its bent construction, prevents water from running back of the gutter at the eaves, and thereby prevents streaking

of the fascia board 17 from this cause. It also prevents water from running down between the fascia board 17 and the rearward wall 22 of the gutter 13, and thus eliminates rusting away of the gutter 13 at this location, or of the gutter brackets or fasteners.

If any leaves, twigs or other foreign matter accumulates on top of the screen 12, the sections of the screen may be removed for cleaning merely by reversing the foregoing procedure of installing it. This consists in grasping the forward edge of the screen and lifting upward upon it, until the downwardly bent abutment portion 43 clears the edge 27 of the flange 26, whereupon the screen may be pulled forward over the flange 26 until its rearward edge portion 40 is completely withdrawn from the groove 37 of the flashing 11. The screen may then be cleaned, and likewise the gutter 13, if any fine particles have fallen through the screen into the gutter. The screen 12 may then be replaced in the same manner in which it was originally installed.

It will be seen from Figure 1 that the groove 37 of the flashing 11 is inclined slightly downward in a direction below the flange 26 of the gutter 13. The purpose of this construction is to bend the screen 12 slightly so that pressure is exerted by its forward edge portion downward against the flange 26. This holds the screen 12 securely in position at all times but permits easy withdrawal thereof when desired.

What I claim is:

1. A gutter-protecting device for attachment to a roof eave and gutter of a building, said gutter protecting device comprising a flashing including an elongated member of sheet material having a plate-like upper supporting portion fitting against the eave, an intermediate portion extending downward from said upper portion past the edge of the eave, and a lower portion extending rearwardly from said intermediate portion and having a generally-horizontal screen-holder thereon; and an elongated reticulated gutter screen having a width sufficient to cover the gutter, said screen having its forward edge portion engageable with the forward edge portion of the gutter and its rearward edge portion secured in said screen holder.

2. A gutter-protecting device for attachment to a roof eave and gutter of a building, said gutter protecting device comprising a flashing including an elongated member of sheet material having a plate-like upper supporting portion fitting against the eave, an intermediate portion extending downward from said upper portion past the edge of the eave, and a lower portion connected to said intermediate portion and having a generally-horizontal screen-receiving recess therein; and an elongated reticulated gutter screen having a width sufficient to cover the gutter, said screen having its forward edge portion engageable with the forward edge portion of the gutter and its rearward edge portion secured in said recess.

3. A gutter-protecting device for attachment to a roof eave and gutter of a building, said gutter protecting device comprising a flashing including an elongated member of sheet material having a plate-like upper supporting portion fitting against the eave, an intermediate portion extending downward from said upper portion past the edge of the eave, and a lower portion extending rearwardly from said intermediate portion and having a generally-horizontal forwardly-directed

screen-receiving recess therein; and an elongated reticulated gutter screen having a width sufficient to cover the gutter, said screen having its forward edge portion engageable with the forward edge portion of the gutter and its rearward edge portion secured in said recess.

4. A gutter-protecting device for attachment to a roof eave and gutter of a building, said gutter protecting device comprising a flashing including an elongated member of sheet material having a plate-like upper supporting portion fitting against the eave, an intermediate portion extending downward from said upper portion past the edge of the eave, and a lower portion extending rearwardly from said intermediate portion, said lower portion being trough-shaped with a generally-horizontal forwardly-extending opening therein; and an elongated reticulated gutter screen having a width sufficient to cover the gutter, said screen having its forward edge portion engageable with the forward edge portion of the gutter and its rearward edge portion secured in said opening.

5. A gutter-protecting device for attachment to a roof eave and gutter of a building, said gutter protecting device comprising a flashing including an elongated member of sheet material having a plate-like upper supporting portion fitting against the eave, an intermediate portion extending downward from said upper portion past the edge of the eave, and a lower portion having a top wall extending rearwardly from said intermediate portion and a bottom wall extending forwardly from the rearward edge of said top wall to form a generally-horizontal screen-receiving trough; and an elongated reticulated gutter screen having a width sufficient to cover the gutter, said screen having its forward edge portion engageable with the forward edge portion of the gutter and its rearward edge portion secured in said trough.

6. A gutter-protecting device for attachment to a roof eave and gutter of a building, said gutter protecting device comprising a flashing including an elongated member of sheet material having a plate-like upper supporting portion fitting against the eave, an intermediate portion extending downward from said upper portion past the edge of the eave, and a lower portion having a top wall extending rearwardly from said intermediate portion and a bottom wall extending forwardly from the rearward edge of said top wall to form a generally-horizontal screen-receiving trough, said bottom wall having a downwardly-directed forward edge portion to facilitate insertion of said screen; and an elongated reticulated gutter screen having a width sufficient to cover the gutter, said screen having its forward edge portion engageable with the forward edge portion of the gutter and its rearward edge portion secured in said trough.
